CLAIM

We claim the ornamental design for a wall-mountable lighting control unit, as shown and described.

DESCRIPTION

FIG. 1 is a perspective view of a wall-mountable lighting control unit according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a wall-mountable lighting control unit according to a second embodiment of our new design.

FIG. 8 is a front view thereof.

FIG. 9 is a left side view thereof.

FIG. 10 is a right side view thereof, the top and bottom views, respectively, of the second embodiment being identical to the top and bottom views of the first embodiment.

FIG. 11 is a perspective view of a wall-mountable lighting control unit according to a third embodiment of our new design; and,

FIG. 12 is a front view thereof, the left side, right side, top and bottom views, respectively, of the third embodiment being identical to the left side, right side, top and bottom views of the second embodiment.

The rear views form no part of the design and are omitted. The portions of the drawings appearing in broken line are for environment only and do not form a part of the design.
